Primary Examiner—Clare E Heflin(74) *Attorney, Agent, or Firm*—Sheppard, Mullin, Richter & Hampton LLP(57) **CLAIM**

I claim the ornamental design for a solar light, as shown and described.

DESCRIPTION

FIG. 1 is a perspective view of a solar light showing the new design;

FIG. 2 is a front elevational view thereof, the left side, right side and rear elevational views being identical images thereof;

FIG. 3 is a top plan view thereof; and,

FIG. 4 is a bottom plan view thereof.

The dotted lines are for illustrative purposes only and form no part of the claimed design.
